UNITED STATES PATENT OFFICE

2,504,257

CLEANSING NOZZLE ATTACHMENT FOR
TOILET BOWLS

Roscoe H. Dunn, Bloomington, Ill.

Application January 17, 1947, Serial No. 722,703

2 Claims. (Cl. 4-7)

1

This invention relates to a toilet seat arrangement.

It is an object of the present invention to provide a cleansing nozzle adapted to be adjusted in and out of a central position over a toilet bowl for the purpose of cleansing the body part after the stool has been made and wherein a saving in the use of toilet paper will be effected.

It is another object of the present invention to provide a simple arrangement including an adjustable valve for controlling the flow of water which can serve as the handle means for effecting the lateral adjustment of the nozzle inwardly to the center of the toilet bowl.

For other objects and for a better understanding of the invention, reference may be had to the following detailed description taken in connection with the accompanying drawings, in which:

Figure 1 is a top plan view of a toilet seat arrangement with the laterally adjustable nozzle device embodying the features of the present invention.

Figure 2 is an enlarged fragmentary cross-sectional view looking in elevation upon the laterally adjustable nozzle device.

Referring now to the figures, 10 represents a toilet seat disposed over a toilet bowl and on which the person using the toilet can be seated. The toilet bowl is indicated at 11. Adapted to be extended over the sides of the bowl 11 is a clamp 12 serving as a support for a laterally slideable pipe 13 having a crooked forward end with a nozzle 14 extending therefrom. The clamp 12 has a bracket 15 with an opening therethrough in which the pipe 13 is slidably contained. The outer end of the pipe 13 is connected to a valve fitting 16 having a hand-operated wheel 17 extended therefrom to effect the opening and closing of a valve 18 therewithin. This valve connects a flexible hose 19 with the reservoir 20 at the rear of the toilet seat 10. This reservoir 20 contains the flushing water, and when the valve 18 is opened, such water will pass through the flexible hose 19, the valve fitting 16 and thence through the pipe 13 to the nozzle device 14. There will be sufficient pressure upon the water to cause the water to rise above the nozzle head 14 sufficiently to contact with the body parts of the person sitting on the seat 10 to flush any fecal

2

matter remaining upon the body parts therefrom. This operation, however, is not effected until the pipe 13 has been slid inwardly against the action of a spring 21 contained on the pipe 13. The handle 17 serves not only to control the valve 18, but as the means which can be grasped to cause the inward movement of the pipe 13. When the hand is removed from the wheel 17, the pipe 13 will be returned to its original position, as shown in full in Figures 1 and 2, and from a dotted line position 22 where the nozzle 14 was centrally located within the opening of the toilet bowl 11.

Having thus described my invention, I claim:

1. A spray device for use on a toilet bowl having a toilet seat over and spaced above said bowl, said device comprising a mounting clamp having depending spring arms to embrace inner and outer sides of the upper edge of the bowl to mount the device on the upper edge of the bowl, a sleeve on the upper part of said clamp and arranged to occupy a position in the space between said bowl and said seat, a relatively short horizontal tube slideable through said sleeve and having an upturned nozzle on its inward end, a valve body on the outer end of said tube arranged for connection to a water supply, a helical spring circumposed on said tube and compressed between said valve body and said sleeve whereby said tube normally occupies an outpressed position wherein said nozzle is positioned close to the upper edge of the bowl, a valve in said valve body, a combined handle projecting therefrom, said handle being arranged to serve both to open and close the valve, and to enable pushing said tube inwardly against the tension of said spring to position said nozzle centrally of the bowl.
2. A spray device for use on a toilet bowl having a toilet seat over and spaced above said bowl, said device comprising a mounting clamp arranged to embrace inner and outer sides of the upper edge of the bowl, a horizontally-disposed sleeve on the upper part of said clamp and arranged to occupy a position in the space between said bowl and said seat, a tube slideably supported in said sleeve, said tube having on its inward end an upturned nozzle and having on its outer end a valve body arranged for connection to a water supply, resilient means interposed between said valve body and said sleeve and operatively connected to said tube for normally urging said tube

to an outpressed position wherein said nozzle is positioned close to the upper edge of the bowl, a valve in said valve body, and a hand-actuable means projecting from said valve body and connected to said valve to serve both to open and close the valve and to enable pushing of said tube inwardly against the tension of said resilient means to position said nozzle centrally of the bowl.
